METHOD OF AND APPARATUS FOR
PRINTING

George R. Brodie, Lower Merion Township, Montgomery County, and William M. Hawkes, Jr., Philadelphia, Pa., assignors to Fred'k H. Levey Co., Inc., New York, N. Y., a corporation of New York

Application October 26, 1948, Serial No. 56,656

5 Claims. (Cl. 101—350)

1

This invention relates to printing and particularly to an improved method of and apparatus for supplying ink to the metal printing plates of cylinder presses.

In web presses, it has been customary for many years to deliver ink from the fountain to the plates on a plate cylinder through a long train, upward to twenty, of inking rollers which rotate and vibrate in order to provide a uniform film of ink on the printing plates. The complicated mechanism required in the usual ink train materially retards the possible speed of operation of the press and consequently its output.

It is the object of the present invention to provide an improved method of inking the plate cylinder of a rotary printing press and apparatus therefor which is simpler and more effective and which permits operation at higher speeds.

Other objects and advantages of the invention will be apparent as it is better understood by reference to the following specification and the accompanying drawing, in which

Fig. 1 represents diagrammatically the essential parts of the inking and printing mechanism; and

Fig. 2 is a side elevation of one of the inking rollers.

In accordance with the present invention, we employ an ink of the quick drying type consisting of a pigmented varnish made up of a resin and a solvent therefor which has a relatively low boiling point and a high vapor pressure at the temperature to which it is subjected for the purpose of drying the ink. Quick drying inks of this type are used extensively in printing magazines and have superseded linseed oil inks during the past sixteen years. Instead of a complicated inking train, we employ a relatively simple arrangement consisting of a hard surfaced rubber roller which contacts the printing plates on the plate cylinder and also a knurled roller to which ink is delivered from a fountain through an intermediate doctor roller. The knurling on the knurled roller is disposed at an angle preferably 45° to the line parallel to the axis of the roller. The roller between the knurled roller and the plate cylinder is provided with a hard rubber surface having a hardness of between 30 and 95 Durometer. The ink is picked up from the fountain by a steel roller revolving therein. An adjustable doctor blade is arranged to limit the amount of ink withdrawn from the fountain. The ink is transferred by the intermediate doctor roller to the knurled roller, which receives a uniform film of the ink and transfers it through the hard surfaced roller to

2

the plates on the cylinder. The knurled roller has the effect of causing the ink to transfer uniformly and in the correct amount to properly ink the surface of the printing plates and thus to secure an impression of high quality on the web as it passes between the plate and impression cylinders. Owing to the simplicity of the inking train, many of the difficulties experienced in the ordinary press are avoided and the speed of the press may be increased materially.

The knurling on the knurled cylinder may vary in dimensions, but is preferably about 175 lines to an inch with a depth not exceeding 0.002 inch. If the knurling is too coarse, the desired effect is not obtained, but it may be finer than indicated with excellent results. The pressure between the knurled roller and the engaging hard surfaced roller may vary from a few pounds to 10,000 pounds per square inch. The combination of the knurled roller with the hard surfaced roller ensures the transfer of the ink in the manner already indicated to the plates on the plate cylinder.

For the purpose of the invention, we employ ink of the quick drying type consisting of a pigmented vehicle made up of a resinous binder and a petroleum hydrocarbon having a relatively low boiling point and a high vapor pressure when subjected to a temperature above normal atmospheric temperature. A characteristic ink of this type is made in accordance with the following formula:

2.00	alkali blue base
15.30	zinc resinate
35	22.60 petroleum hydrocarbon, B. Pt. 450° F.
	0.10 water
	0.75 gilsonite
	0.68 rosin
40	1.07 petroleum hydrocarbon, B. Pt. 503° F.
	3.20 wetting agent (tallicin 105)
	16.00 carbon black
	6.30 calcium carbonate pigment
	32.00 petroleum hydrocarbon, B. Pt. 381° F.

45 100.00

It is to be understood that in describing this typical ink the invention is not thereby limited, because it is apparent that numerous combinations involving substitutions of resins, pigments and other ingredients of the ink may be made. Thus, the ink may be of any desired color by substituting suitable pigments. There are numerous resins which are adapted to be dissolved in the solvent to produce varnishes suitable for the pur-

pose. All of this is well within the skill of ink makers familiar with this type of ink.

The ink should, however, have a flowing characteristic somewhat different from ordinary magazine inks such as are used with extended ink trains, the ink employed in accordance with the present invention being somewhat softer. The preferred constants for the ink are determined at 25° F. The plastic viscosity is 10.1 poises, and the yield value is 57.3 dynes per square centimeter. This again is merely illustrative and is subject to variations. Such variation is obtained by modifying the proportions of the solvent in the composition as above described.

Referring to the drawing, 5 indicates an impression cylinder, and 6 the plate cylinder carrying metallic plates having an appropriate type surface. The impression is transferred to a web 7 which passes between the plate and impression cylinders. Engaging the plates on the plate cylinder is a hard surfaced rubber roller 8 having the characteristic hardness as above described. The roller 8 is engaged by a roller 9 of metal having a knurled surface of the character hereinbefore described. An intermediate doctor roller 10 of rubber or other suitable material is disposed between and in engagement with the roller 9 and a steel roller 11 which is adapted to rotate in a fountain 12 carrying the ink 13. The roller 10 is mounted on an arm 10' which vibrates to alternately engage the roller 10 with the roller 11 and the knurled roller 9. A doctor blade 14 is supported on a bracket 15 and is adjustable by means of thumb screws 16 to vary the distance between the surface of the roller 11 and the edge of the doctor blade in order to limit the amount of ink withdrawn from the fountain as the roller 11 rotates in the direction indicated by the arrow on the drawing. Thus, the ink from the fountain is transferred to the intermediate doctor roller 10, thence to the roller 9 and through the surface of the roller 8 to the printing surface on the plate cylinder. By adjusting the doctor blade 14, the amount of ink supplied to the train may be varied.

The web 7 may be carried around a steam drum or other heating device 17 and over an idler roll 18. It may be rewound after the initial impression. However, if the web is to be perfected by printing on the reverse side, it may be delivered from the idler roll 18 to a second printing unit identical with that previously described, to receive an impression on the reverse side. Thereafter the web may be heated again by passing over a steam drum similar to the drum 17 to dry the ink. The web may then be rewound, cut or otherwise disposed of.

Among the advantages of the apparatus is the relative inexpensiveness of the apparatus and ease of handling of the ink, and particularly the avoidance of long trains of inking rollers as here-

tofore used in web printing presses. The advantage resulting from the elimination of the complicated inking trains is the increased speed at which the printing operation may be carried on. The method and apparatus are adapted for printing of a wide variety of materials, including books, magazines, newspapers, catalogs, telephone directories and the like.

Various changes may be made in the details of the procedure as described and in the apparatus employed without departing from the invention or sacrificing the advantages thereof.

We claim:

1. The method of inking metallic printing plates which comprises transferring ink from a source thereof to a rotating smooth metal surface, thence to a rubber rotating surface, thence to a knurled rotating surface, thence to a rotating smooth hard rubber surface, and finally to the rotating printing plate surface.

2. The method of inking metallic printing plates which comprises transferring ink from a source thereof to a rotating smooth metal surface, thence to a rubber rotating surface, thence to a knurled rotating surface, thence to a rotating smooth rubber surface having a hardness of 30 to 95 Durometer, and finally to the rotating printing plate surface.

3. In a printing press, a plate cylinder, an impression cylinder and an inking train comprising a fountain, a rotating metal roller adapted to deliver ink from the fountain, a knurled roller, an intermediate doctor roller having a rubber surface engageable with said ink-delivering metal roller and said knurled roller, and a roller having a hard rubber surface, said hard surfaced roller engaging the knurled roller and the plate cylinder.

4. The printing press of claim 3 having a doctor blade adjustable with respect to the surface of said ink-delivering metal roller to control the amount of ink withdrawn by said roller from the fountain.

5. The printing press of claim 3 in which the surface of the hard-surfaced roller has a hardness of 30 to 95 Durometer.
